UNITED STATES PATENT OFFICE.

WILLIAM H. WILDER, OF GARDNER, MASSACHUSETTS.

DESIGN FOR AN OIL-STOVE.

SPECIFICATION forming part of Design No. 30,567, dated April 18, 1899.

Application filed March 23, 1899. Serial No. 710,254. Term of patent 14 years.

To all whom it may concern:

Be it known that I, WILLIAM H. WILDER, of Gardner, Massachusetts, have invented and produced a new and original Design for Oil-Stoves, of which the following is a description.

In the accompanying drawings, Figure 1 shows the invention in front elevation. Fig. 2 is a partial end view, the base part being in section. Fig. 3 is a plan view. Fig. 4 is an end elevation. Fig. 5 is a horizontal section on line $x x$, Fig. 1.

The leading feature of the design is in the general configuration of the stove frame or casing. The base A of the stove is of rectangular shape and of box form, having a door B and scrolls $a b$ on the front and ends. Upon this base, surmounting it, is a body part B', resting upon an interposed plate C. The

part B' is of the same general shape as the base A, except that it is of greater height and has rounded corners c. This gives a pleasing effect in connection with the square corners c' of the base and as the body part is of slightly smaller diameter in length and width than the base A. The body part B' has a door d, with elongated openings e therein, and forming the top of the body part is a cover-plate D, having openings f and grates fitted thereto.

What I claim is—

The design for an oil-stove as herein shown and described.

In testimony whereof I affix my signature in presence of two witnesses.

WILLIAM H. WILDER.

Witnesses:

H. M. GATES,
M. C. LYONS.
